CLAIM

The ornamental design for a facia gable extrusion for a building structure, as shown and described.

DESCRIPTION

FIG. 1 is a perspective view of a facia gable extrusion for a building structure showing my new design;

FIG. 2 is a end view thereof, the other end being a mirror image;

FIG. 3 is a rear view thereof;

FIG. 4 is a front view thereof;

FIG. 5 is a bottom view thereof; and,

FIG. 6 is a top view thereof.
